Application June 16, 1947, Serial No. 754,918

11 Claims. (Cl. 134—200)

1

This invention relates to timing device and more particularly to a device of this character for automatically initiating in their proper timed relation, the series of steps which occur in the operation of a dish-washing machine.

The usual dish-washing machine involves a sequence of steps or operations which are carried out to most effectively clean the dishes. The first step should be one which merely supplies fresh water to wash off the loose residue. After a short interval of time for this preliminary wash, the dishes should be subjected to the washing action of a liquid containing soap or some other detergent. In this operation, it is important that the wash water be re-used so that the soap or detergent is not wasted and during this time the drain should therefore be closed. This cleansing operation should proceed for a moderate length of time and thereafter the drain should be opened so that the wash water can flow away from the dishes. Thereafter, the dishes should be sprayed with fresh water for a short period of time to remove any traces of the soap or detergent which may be left upon the dishes. Following this final washing step, the flow of wash water should be cut off so that the dishes can dry and in order to best permit this drying action, the cover of the machine should be opened so that the moisture-laden air can escape and the relatively drier air of the atmosphere can come into contact with and serve to dry the dishes.

The timing device of the present invention initiates these several steps in their proper sequential order and, moreover, carries out each step during the proper time interval. After these steps have once been set in operation by a person, they proceed in their regular order until the dishes are washed and, thereafter, the cover is opened so that the dishes will dry and the complete operation will have been carried out.

It is an important feature of the invention that the timing device is actuated by the water pressure of the supply of water which is utilized to wash the dishes. As a consequence, the timing device is of simple construction and makes use of the same water connection established for washing the dishes.

A preferred embodiment of the invention is illustrated in the accompanying drawings in which:

Figure 1 is a plan view of a dish-washing machine to which the timing device of the invention has been applied,

Figure 2 is a front elevational view of Figure 1,

Figure 3 is a sectional view on the line 3—3 of Figure 1 on an enlarged scale,

Figure 4 is a sectional view on the line 4—4 of Figure 1 on an enlarged scale,

Figure 5 is a sectional view on the line 5—5 of Figure 2 on an enlarged scale,

2

Figure 6 is a sectional view on the line 6—6 of Figure 5, and

Figure 7 is a left hand side elevational view of the linkage and shaft of Figure 6.

The dish-washing machine which is here illustrated includes a tub or shell 10 having a cylindrical side wall 11, and a bottom wall 12. At the top of the tub 10 is a top plate 13, which is flush with the top rim of the side wall 11. A lid or cover plate 14 for the shell 10 is pivoted about hinge shafts 15 to the rearward portion of the top plate 13. Springs 16 are positioned upon the shafts 15 and are under such torsion that they tend to lift up the cover plate 14 to an open position.

To hold the cover plate 14 downwardly in its closed position it is provided with a depending pin 17 (see Fig. 2) at its forward free edge, and pin 17 is formed with an upwardly facing shoulder 18 at its lower end. A retractable latch 19 engages over shoulder 18 to hold the cover plate in its downward position. The latch 19 is provided with an enlarged tail portion 21 and the latch 19 is guided for reciprocatory motion toward and away from the pin 17 by means of guide rails 22 on opposite sides of the latch. These rails are carried on the under-side of top plate 13. A pin 23 projects from the latch 19 through one or both of the guide rails 22 to limit the endwise movement of latch 19.

A spring 24 bears against the enlarged portion 21 to urge the latch 19 toward the pin 17. It will be observed that the engaging end of latch 19 is bevelled so that a mere downward motion on the cover plate 14 will serve to force the latch 19 to a retracted position against the action of spring 24 so that the shoulder 18 can become engaged under the latch 19. To disengage the latch 19, a pull rod 25 is provided and this pull rod has an inturned end which enters a slot 26 in the tail portion 21 of the latch. A spring 27 urges the pull rod 25 in a direction which tends to disengage the latch, but it has insufficient pressure to bring this action about and serves merely to hold the parts in the proper relationship until a pull is exerted upon rod 25 at the proper time. This means for exerting a pull upon the rod 25 will be described later.

A bracket 28, depending from the top plate 13, provides a seat for spring 24 and also for spring 27, to back them up. Rod 25 passes through a hole in bracket 28.

Rotatably mounted within the tub 10 is any suitable means for supporting the dishes to be washed. As a suitable construction for this purpose is well known, an illustration of this detail has not been included but it will be understood that any open basket formation may be utilized. It is here contemplated that the basket, or like carrier, will be rotatable about a center vertical

pivot so that the basket may rotate and bring all faces of all of the dishes into the streams of water which are to effect the cleansing action.

These streams of water are projected upwardly from the bottom wall 12 of the tub. As here shown, this is accomplished by providing a plurality of jets 30 which pass through fluid tight openings in the bottom wall 12 of the tub. All of the jets 30 are connected to a common pipe 31 which serves as a manifold, and the pipe 31 is connected at 32 to the timing device. In the illustrated apparatus, all or most of the jets 30 are inclined from the vertical so that they will direct streams against the dishes at such an angle that the carrier for the dishes will thereby be rotated about its support. However, it is to be understood that the invention is equally as applicable to a dish-washer having a motor driven dish-carrier and other types of water projecting means for washing the dishes.

The bottom wall 12 of the shell 10 preferably slopes downwardly to a drain 33 as is best shown in Figure 6. The drain 33 is provided with an inner guide surface 34 and with an upwardly facing valve seating surface 35. Vertically movable within the guide surface 34 is a tubular valve member 36 which performs the combined function of a valve head to close the drain and also serves to maintain a given level of water within the tub 10. The valve member 36 is formed at a point approximately centrally of its height with a peripheral flange which provides a valve seating surface 37 to rest upon the seating surface 35. When the member 36 is in its lowermost position and the surfaces 35 and 37 are in contact with each other, liquid cannot immediately escape into the drain 33. When the member 36 is lifted, however, openings 38 in the side wall of the member 36 below flange 37 are opened to the interior of the tub 10 so that the water can freely pass into the drain.

The top of tubular member 36 is open so that water can flow over the top rim or edge 39 and into the tubular member 36 and then pass downwardly into the drain. Therefore, when the member 36 is in its lowermost position and valve seating surfaces 35 and 37 are in contact with each other, the water within the shell 10 cannot immediately pass into the drain 33, but after the level of the water has risen to the top edge 39 of member 36 the water can enter this open top and fall into the drain. It will, therefore, be appreciated that the position of the rim 39 upwardly within the shell 10 determines the level of the liquid which will be maintained in the shell 10 after the valve member 36 has descended to its lower position.

It may be mentioned at this point that during the washing step in which soap or a detergent is in the body of water being maintained at the bottom of the tub 10, the streams of water issuing from the jets 30 pick up this soapy water and project it against the dishes. For this reason, the orifices of the jets 30 are below the top rim 39 of the valve member 36 and as a consequence the streams of fresh water from the jets 30 will be projected through the soapy body of water and carry a considerable amount of this soapy water upwardly against the dishes.

It may also be mentioned at this point that during the initial flushing action with fresh water to wash off the residue on the dishes there will not be sufficient height of water accumulated in the bottom of the tub 10 to overlie the jets 30. As a consequence there will not be a pick-up of

water from the bottom of the tub and the full strength of the streams from the jets will be directed upon the dishes. These strong streams will remove the loose food particles from the dishes. After a sufficient amount of water has entered the tub so that it overlies the jets 30, the soapy water will be carried against the dishes to effect the thorough washing operation. After the washing operation is over the valve member 36 must be lifted to its upper position so that the soapy water can drain away and also so that the fresh water which is introduced to remove the soapy material from the dishes will also immediately escape through the drain 33.

To operate the valve member 36, a shaft 42 which passes transversely through the drain 33 is provided. This shaft 42 has affixed thereto a cam 43 so that an arcuate rotation of the shaft 42 will cause the cam 43 to bear against the underside of a cross bar 41 of valve member 36 and left member 36, or conversely, to permit it to move to its downward position. To give the shaft 42 this arcuate movement a lever 44 is affixed to shaft 42 and a pull rod 45 is pivotally connected to the outer end of lever 44. The means for operating the pull rod 45 will be explained later.

The timing device of the invention performs several functions. It operates the pull rod 45 which serves to lift and lower the valve member 36, the pull rod 25 which serves to retract the latch 19, and it also delivers liquid into the manifold pipe 31 at and for the proper period of time. Thus, the addition of the timing device, to the dishwashing machine makes the operation of the machine fully automatic.

The timing device includes a body 47 which has a lower cylindrical chamber 48. Chamber 48 is closed at its lower end by a cover plate 49 which is affixed to the body 47. The upper portion of body 47 is formed with a cylindrical chamber 51, which is of less diameter than the chamber 48. Chamber 51 is in axial alignment with the cylindrical chamber 48.

Operating within the chambers 48 and 51 is a piston 52. The lower portion of piston 52 is enlarged to fit the cylindrical surface 48 and a packing material 53 therein provides a liquid-tight seal between the lower end of the piston and the surface 48. The piston 52 passes upwardly through the top of the body 47 and a packing material 54 carried by the body 47 prevents escape of liquid to the outside of the body around piston 52. Above the lowermost end of piston 52, it is formed with a peripheral flange in which is located packing material 55. This packing material at 55 is in sealing engagement with the inner surface of the cylindrical chamber 51. Above the sealing material 55 the piston 52 is formed with a shoulder 56 which limits the upward movement of the piston 52 by contact against the body 47.

Extending transversely of the body 47 is a bore 57-58 and it will be observed that the bore portion 57 is on one side of the chamber 48 and that the bore portion 58 is on the other side of chamber 48. Also, the bore 57-58 is positioned between the chamber 48 and the smaller chamber 51 and therefore communicates with both of these chambers. This bore 57-58 may be formed by drilling cross-wise through the body 47 and thereafter closing the ends by means of plugs 59.

The bore at 57 receives the water which is supplied under pressure. Although water may be

delivered directly to this bore 57, in the present embodiment of the invention, a sieve 61 is provided in the path of the incoming stream to serve to filter the incoming water. The filter screen 61 is positioned in a chamber 62 which is formed in the body 47 to one side of the cylindrical chamber 48. The upper end of the screen 61 is open and seats against an internal shoulder 63 formed at the top of chamber 62. A plug 64 is screwed into the lower end of chamber 62 to close it and this plug 64 bears against a spring 65 carried by the lower end of screen 61 so that the screen 61 is urged upwardly into sealing engagement with the shoulder 63.

An inlet opening 66 is formed in the side wall of chamber 62 and the supply pipe 67 is connected to a source of water to supply water under pressure through this opening 66 and into the chamber 62. It is apparent that the water must all flow through the screen 61 in order to enter the inlet bore 57.

The outlet bore 58 communicates with a passageway 68 which is formed in the body 47 and opens outwardly at the bottom of this body 47. From the lower end of passageway 68 is a port 69 which enters into the lower end of the cylindrical chamber 48. The lowermost end of passageway 68 is closed by means of a plug 71.

It is apparent that the incoming water can flow from the inlet bore 57 around the piston 52 and into the outlet bore 58, and can thereafter flow downwardly through the passageway 68 and through port 69 into the cylindrical chamber 48. To restrict this flow so that only a small amount of water can bleed into the chamber 48, a capillary tube 72 is positioned within the passageway 68. This capillary tube 72 may be supported in position by having it attached to a sleeve 73, threaded into the lower part of passageway 68.

The opening through the capillary tube 72 should be so small that in conjunction with the length of this capillary tube 72 only a small amount of water can pass through the tube in a definite time interval. It has been found that the use of this capillary tube is more satisfactory to regulate the flow and obtain a uniformity of operation than could be achieved for example by means of a simple small port opening.

It will be apparent that the water which is supplied to the under-side of piston 52 through port 69 will force the piston 52 upwardly to the position of Figure 3. Although the water is also acting downwardly upon the upper side of the flange at the lower end of piston 52, since the under-side of piston 52 has a greater effective area, the piston 52 will be pushed upwardly. However, it will be apparent that if the water pressure below piston 52 is allowed to escape, the water pressure acting downwardly on piston 52 will cause the piston 52 to move downwardly.

To permit the escape of the water beneath piston 52, the lower part of cylindrical chamber 48 is provided with an outlet opening 74. The outlet opening 74 communicates with a chamber 75 (Fig. 4) which in turn communicates with a passageway 76. The passageway 76 is connected by means of a pipe 77 to the drain 33. The flow of fluid from the chamber 75 into the passageway 76 is controlled by a valve head 78 carried at the lower end of a valve rod 79. The valve rod 79 passes upwardly through the body 47 and escape of water is prevented by a packing material 81 carried by the rod 79. A spring 82 surrounds the valve rod 79 outside of the body 47 and bears at its lower end upon the body 47 and

at its upper end against a ring 83 affixed to the valve rod, to urge the valve head 78 to closed position.

Spring 82 therefore serves to hold the valve head 78 on its seat so that the water which has entered the cylindrical chamber 48 through port 69 cannot escape into the pipe 77 and into the drain 33. To unseat the valve head 78 a push button 84 is affixed to the top end of rod 79 and this push button 84 is located in an opening in the top plate 13 so that it is readily available to the operator.

When the valve head 78 is upon its seat, the water cannot escape from the cylindrical chamber 48 and consequently the piston 52 is forced to its uppermost position. As has been mentioned, this is because the exposed area on the under side of the piston 52 is greater than the effective area on the upper side of the piston 52. So long as the valve head 78 remains upon its seat, therefore, the piston 52 will remain in its uppermost position and the incoming water supply will be sealed within the timing body. The water cannot escape above packing material 55 and it cannot escape out of chambers 48 and 75. However, when the valve head 78 is removed from its seat by manually depressing the button 84 the liquid within the cylindrical chamber 48 will escape past the valve head 78 and through pipe 77 into the drain 33.

As the water pressure beneath the piston 52 will be relieved when valve head 78 is opened, the force exerted by the incoming water upon the upper effective surface of the piston 52, will cause the piston 52 to rapidly descend to its lowermost position. This descent of piston 52 will not be interfered with by the water bleeding into the chamber 48 through port 69, because of the extremely small size of the opening through capillary tube 72 relative to the outlet opening 74 and the communication from this outlet opening to the drain.

From Figure 3 it will be apparent that as soon as the packing material 55 has moved below the surface 51 the water within the inlet bore 57 can pass around the piston 52 and into an outlet opening 86 in the upper part of the timer body. The outlet opening 86 is connected by the aforesaid coupling means 32 to the manifold pipe 31 which supplies water to the jets 39 within the tub 10. During the time that the packing material 55 is below the surface 51 the water supplied through incoming pipe 67 will pass through the timer body and into the manifold pipe 31 and during this entire same period of time streams of water will continue to issue from the jets 39.

As a safety provision in the event of a failure in the water supply, an air inlet one-way valve 87 is provided. This valve 87 is contained in a bored plug 88 and so long as the water pressure is maintained the valve 87 will be forced to an upper position and against its seat to prevent escape of water from the bored plug 88. However, if a failure of the water pressure supply occurs so that a suction occurs in the supply pipe 67, the valve 87 will immediately drop and permit air to enter through the bored plug 88 and through the timer body and into the supply pipe 67. This will prevent the possibility of the wash water within the bottom of the tub 10 from being sucked into the water supply and thereby causing its contamination.

It has been pointed out that the timing mechanism serves to unlatch the cover 14 at the proper time so that when the dishes are cleaned this

cover will automatically open. To accomplish this purpose the uppermost part of the piston 52 is formed with a flanged enlargement 91 such as by affixing a washer to the upper part of piston 52 by means of a screw 90. A trip lever 92 is pivotally attached to a bracket 93 secured to the timer body. The pull rod 25 is pivotally connected to one arm of lever 92 and the other arm of trip lever 92 extends into the path of the flanged enlargement 91 at the top of piston 52.

During the downward movement of piston 52 from its position in Figure 3 the flanged enlargement 91 will swing the trip lever 92 in a direction to exert a push upon the rod 25 and because of the slot connection at 26 this will have no effect on the latch 16. However, during the upward movement of the piston 52, when the flanged enlargement 91 strikes against the trip lever 92 a pull will be exerted upon the rod 25 and this in turn will withdraw the latch 16 from the shoulder 18 and release the locking pin 17. As a consequence the springs 16 will swing the cover or lid 14 upwardly to an open position.

It has also been mentioned that the timing device serves to open and close the drain valve 36 at the proper times. To accomplish these operations, a pin or stud 95 is affixed to the uppermost part of the piston 52 by means of screw 90. The upper end of the pull rod 45 is formed with an enlarged head 96 which is slotted, and pin 95 engages in this slot. As has been pointed out, pull rod 45 actuates the lifting cam 43 which acts upon the drain valve member 36. The slotted connection between pin 95 and head 96 permits a lost motion connection so that the longer travel of piston 52 relative to the necessary movement of rod 45 will be accommodated and so that valve 36 will not be lifted until the proper time.

The timing device may be supported in any convenient manner. As here shown, a bracket plate 97 is secured as by welding to the outer side of the tub 10. The body 47 is attached to plate 97 by means of bolts 98 which pass through bosses 99 of the body 47.

In considering the complete operation of the mechanism it may first be pointed out that during stand-by periods, the water pressure from supply pipe 61 is maintained within the cylindrical chamber 48 on the under side of piston 52 to keep this piston in its proper position. The packing material 55 during this time serves as a valve to prevent the water from passing to the outlet opening 36 and into the manifold pipe 31. Also, as valve 73 will be upon its seat, water cannot escape from the chamber 48 and there will consequently be no loss of water from the water supply.

When the machine is to be used for washing dishes, the dishes are placed in the basket or other dish carrier within the shell or tub 10 and the lid 14 is then closed. The latch 16 will engage the shoulder 18 of pin 17 to hold the lid down against the action of springs 16. It will be observed that at this time the drain valve 36 is held in its open position by means of the pin 95 which is holding pull rod 45 in its upper position.

When the push button 84 is depressed to initiate the washing action, valve 73 is removed from its seat and the water beneath piston 52 escapes through opening 74, through pipe 71 and into drain 33. The piston 52 thereupon moves downwardly rapidly and as soon as the packing material 55 passes below the surface 51 the in-

coming water is permitted to flow into the outlet 36 and through outlet pipe 31 to the jets 30.

When the piston 52 has reached its lowermost position the seating surface 37 of drain valve member 36 will rest upon its seat 35 so that the inflowing water cannot escape from tub 10. At this time the push button 84 must be released and the soap or other detergent must be added to the tub 10.

During the initial period that the water is flowing through jets 30, the fresh water will impinge upon the dishes to remove the loose residue which is upon them. These will be strong streams, because not enough water will have entered the tub to overlie the jets 30.

The water which is entering through jets 30 into the tub 10 will collect at the bottom of the tub 10 until it reaches the top rim 39 of valve member 36. As has been pointed out the position of this top rim 39 of valve member 36 determines the liquid level which will exist in the tub 10 during the washing operation. It has been pointed out, also, that during this washing step the fresh water issuing from jets 30 passes through the body of soapy water at the bottom of the tub 10 and carries this soapy water against the dishes.

When valve 73 is permitted to close by releasing the push button 84, the water which is bleeding into the cylindrical chamber 48 from the port 69 will serve to gradually move the piston 52 in an upward direction. As the water delivered to chamber 48 must pass through the capillary tube 72, it is evident that a prolonged period of time will be required to move the piston through its entire upward movement. By a proper selection of the capillary tube 72 the time interval for the complete rise of piston 52 can be predetermined.

When the piston 52 has moved upwardly far enough for the pin 95 to move through the full length of the slotted head 96, the pull rod 45 will be moved upwardly and this will turn the cam 43 to lift the drain valve member 36. This lifting movement of the drain valve member 36 should occur before the packing material 55 has reached the lower end of surface 51. It will therefore be appreciated that the drain valve 36 will be opened and that the liquid in the bottom of the tub 10 can drain away before the supply of water to the jets 30 is shut off by the valving action of packing material 55. The fresh water which flows through jets 30 at this time will serve to wash the soapy water off of the dishes and down the drain.

Continued upward movement of the piston 52 will cause the packing material 55 to reach the cylindrical surface 51 and because of the valving action which then occurs water will be shut off from the outlet 36 and from the pipe 31 and jets 30. As soon as this has occurred, the flanged enlargement 91 at the top of the piston 52 should strike against the trip lever 92 to exert a pull on rod 25. This will withdraw the latch 16 from the shoulder 18 and release pin 17 so that the cover or lid 14 can swing upwardly to an opened position under the action of springs 16.

The timing mechanism has at this time assumed its normal stand-by position, so that when the net washing operation is intended to take place the cycle of events which has just been described may be repeated.

What is claimed is:

1. The combination with a dishwashing machine having spray jets for directing the water

upon the dishes, of a device for determining the amount of time during which the water flows to said jets, said device comprising a body with an internal cylindrical chamber, having a water inlet and an outlet, said inlet being connectable to a source of water under pressure and said outlet being connectable to said spray jets, valve means including a reciprocating piston within said chamber actuated by and controlling the flow of water from said inlet to said outlet, said piston having means mounted thereon and below the water inlet and outlet forming a liquid-tight seal with the wall of said chamber and means including a capillary tube for by-passing a reduced flow of water from said inlet to the said chamber below said sealing means whereby the action of said piston in moving said valve means to open position is restricted.

2. The combination with a dishwashing machine having spray jets for directing the water upon the dishes of a device for determining the amount of time during which the water flows to said jets said device comprising a body with an internal cylindrical chamber having a water inlet and an outlet, said inlet being connectable to a source of water under pressure and said outlet being connectable to said spray jets, valve means including a reciprocating piston within said chamber actuated by and controlling the flow of water from said inlet to said outlet, said piston having means mounted thereon and below the water inlet and outlet forming a liquid-tight seal with the wall of the said chamber, means including a capillary tube for by-passing a reduced flow of water from said inlet to said chamber below said sealing means whereby the action of said piston in moving said valve means to an open position is restricted and said body having a second outlet from said chamber for exhausting the water acting on the under side of said piston thereby permitting the movement of said valve means to open position, and valve means for opening and closing said second outlet, said last mentioned valve means being operable independently of the level of water in said dishwashing machine.

3. The combination with a dishwashing machine having spray jets to direct the water upon the dishes and a valved drain outlet, of a device for determining the amount of time the water flows to said jets, said device comprising a body with an internal cylindrical chamber, having a water inlet and an outlet, said inlet being connectable to a source of water under pressure and said outlet being connectable to said spray jets, valve means including a reciprocating piston within said chamber actuated by and controlling the flow of water from said inlet to said outlet, said piston having means mounted thereon and below the water inlet and outlet forming a liquid-tight seal with the wall of the said chamber, said piston also being operatively connected to said valved drain whereby upon a predetermined movement of said piston said valved drain is opened and means for by-passing a reduced flow of water into said chamber below said sealing means and for urging said piston to move said valve means to a closed position.

4. The combination with a dishwashing machine having spray jets for directing the water upon the dishes and a latched cover biased to open position, of a device for determining the time the water flows to said jets, said device comprising a body having an internal cylindrical chamber provided with an inlet and an outlet,

said inlet being connectable to a source of water under pressure and said outlet being connectable to said spray jets, valve means including a reciprocating piston actuated by and controlling the flow of water from said inlet to said outlet, said piston having means mounted thereon and below the water inlet and outlet forming a liquid-tight seal with the wall of the said chamber, said piston also being operatively connected to said cover whereby said cover is unlatched upon a predetermined movement of said piston and means for by-passing a reduced flow of water into said chamber below said sealing means and for urging said piston to move said valve means to a closed position.

5. The combination with a dishwashing machine having spray jets for directing the water upon the dishes, a latched cover biased to open position and a valved drain outlet, of a device for determining the length of time the water flows to said jets, said device comprising a body having an internal cylindrical chamber provided with an inlet and outlet, said inlet being connectable to a source of water under pressure and said outlet being connectable to said spray jets, valve means including a reciprocating piston within said chamber actuated by and controlling the flow of water from said inlet to said outlet, said piston having means mounted thereon and below the water inlet and outlet forming a liquid-tight seal with the wall of the said chamber, means operatively connecting said piston to said cover and said valved drain whereby upon predetermined movements of said piston said cover is unlatched and said valved drain is opened, and means for by-passing a reduced flow of water into said chamber below said sealing means and for urging said piston to move said valve means to a closed position.

6. The combination with a dishwashing machine having spray jets for directing the water upon the dishes, of a device for determining the amount of time during which the water flows to said jets, said device comprising a body having differentially diametered, coaxial internal chambers in open communication with one another, said body also having a water inlet at the point of juncture of said chambers, and an outlet from the smaller chamber at a point remote from the larger chamber, valve means including a reciprocating piston within said chambers actuated by and controlling the flow of water from said inlet to said outlet, said piston having means mounted thereon and below the water inlet and outlet forming a liquid-tight seal with the wall of the larger chamber and means including a capillary tube for by-passing a reduced flow of water from said inlet to said larger chamber below said sealing means whereby the movement of said piston in opening said valve means is restricted.

7. The combination with a dishwashing machine having spray jets for directing the water upon the dishes, of a device for determining the amount of time during which the water flows to said jets, said device comprising a body having differentially diametered coaxial internal chambers in open communication with one another, said body also having a water inlet at the point of juncture of said chambers and an outlet from the smaller chamber at a point remote from the larger chamber, valve means including a reciprocating piston within said chambers actuated by and controlling the flow of water from said inlet to said outlet, said piston having means mounted

11

thereon and below the water inlet and outlet forming a liquid-tight seal with the wall of the larger chamber, means including a capillary tube for by-passing a reduced flow of water from said inlet to said larger chamber below said sealing means whereby the movement of said piston within said larger chamber and in opening said valve means is restricted and said body having an outlet from said larger chamber for exhausting the water acting on the piston within said larger chamber, whereby the movement of said valve means to open position is permitted, and valve means for opening and closing said second mentioned outlet, said last mentioned valve means being operable independently of the water level in said dishwashing machine.

8. The combination with a dishwashing machine having spray jets for directing the water upon the dishes and a valved drain, of a device for determining the amount of time during which the water flows to said jets, said device comprising a body having differentially diametered coaxial internal chambers in open communication with one another, said body also having a water inlet at the point of juncture of said chambers and an outlet from the smaller chamber at a point remote from the larger chamber, valve means including a reciprocating piston within said chambers actuated by and controlling the flow of water from said inlet to said outlet, said piston having means mounted thereon and below the water inlet and outlet forming a liquid-tight seal with the wall of the larger chamber, means for by-passing a reduced flow of water from said inlet to said larger chamber below said sealing means whereby movement of said piston within said larger chamber is restricted and means operatively connecting said piston to said valved drain whereby upon a predetermined movement of said piston said valved drain is opened.

9. The combination with a dishwashing machine having spray jets for directing the water upon the dishes, a latched lid biased to open position and a valved drain, of a device for determining the amount of time during which the water flows to said jets, said device comprising a body having differentially diametered coaxial internal chambers, in open communication with one another, said body also having a water inlet at the point of juncture of said chambers and an outlet from the smaller chamber at a point remote from the larger chamber, valve means including a reciprocating piston within said chambers actuated by and controlling the flow of water from said inlet to said outlet, said piston having means mounted thereon and below the water inlet and outlet forming a liquid-tight seal with the wall of the larger chamber, means including a capillary tube for by-passing a reduced flow of water from said inlet to said larger chamber below said sealing means whereby movement of said piston within said larger chamber is restricted and means operatively connecting said piston to said valved drain and said latched lid whereby upon predetermined movements of said piston said valved drain and said latched lid are opened.

10. The combination with a dishwashing machine having spray jets for directing the water upon the dishes, a latched lid biased to open position and a valved drain, of a device for determining the amount of time during which the water flows to said jets, said device comprising a body having differentially diametered coaxial internal chambers in open communication with

5 one another, said body also having a water inlet at the point of juncture of said chambers and an outlet from the smaller chamber at a point remote from the larger chamber, valve means including a reciprocating piston within said chambers actuated by and controlling the flow of water from said inlet to said outlet, said piston having means mounted thereon below the water inlet and outlet forming a liquid-tight seal with the wall of the larger chamber, means including a capillary tube for by-passing a reduced flow of water from said inlet to said larger chamber below said sealing means, whereby movement of said piston within said larger chamber is restricted, a valve operative independently of the water level in said dishwashing machine and controlling an outlet from said larger chamber for exhausting the water acting on the piston within said larger chamber, and means operatively connecting said piston to said valved drain and said latched lid, whereby upon predetermined movements of said piston said valved drain and said latched lid are opened.

11. The combination with a dishwashing machine having spray jets for directing the water upon the dishes, and a latched lid biased to open position, of a device for determining the amount of time during which the water flows to said jets, said device comprising a body having differentially diametered coaxial internal chambers in open communication with one another, said body also having a water inlet at the point of juncture of said chambers and an outlet from the smaller chamber at a point remote from the larger chamber, valve means including a reciprocating piston within said chambers actuated by and controlling the flow of water from said inlet to said outlet, said piston having means mounted thereon and below the water inlet and outlet forming a liquid-tight seal with the wall of said larger chamber means including a capillary tube for by-passing a reduced flow of water from said inlet to said larger chamber below said sealing means whereby movement of said piston within said larger chamber is restricted, means operatively connecting said piston to said latched lid whereby upon a predetermined movement of said piston said latched lid is opened, and a valve operative independently of the water level in said dishwashing machine and controlling an outlet from said larger chamber for exhausting the water acting on said piston within said larger chamber.
